PUMP

Andre J. Meyer, Detroit, Mich., assignor to Continental Motors Corporation, Detroit, Mich., a corporation of Virginia

Application February 9, 1931, Serial No. 514,395

14 Claims. (Cl. 103—84)

My invention relates to pumps and more particularly to fuel pumps adapted for use with internal combustion engines, although the principle of my invention may be incorporated in other 5 types of pumps and in pumps other than those employed with internal combustion engines.

An object of my present invention is to construct a pump having generally improved pumping characteristics.

10 Another object of my invention is to minimize the manufacturing costs of a pump and, in particular, a fuel pump for engines and the like, by providing a compact pump structure employing a minimum of economically manufactured parts 15 which may be readily assembled with a minimum of time and labor.

A further object of my invention is to construct a novel fuel pump for engines or other like machines by providing a novel pump wherein 20 a fluid is moved by subjecting a film of such fluid to a moving pump element, thereby utilizing the adhesive and viscous characteristic of such fluid for transferring motion from said moving pump element to the fluid.

25 For a more detailed understanding of my invention, reference may be had to the accompanying drawing which illustrates one form which my invention may assume, and in which:

Figure 1 is a side elevational view of an engine 30 employing a fuel pump constructed in accordance with my invention,

Figure 2 is a sectional view of the pump taken on the line 2—2 of Figure 1.

Figure 3 is a sectional view of the pump taken 35 on the line 3—3 of Figure 2,

Figure 4 is a detail sectional view of the pump drive, and

Figure 5 is a detail sectional view of one of the pumping units.

40 My pump A as shown in the accompanying drawing illustrates a preferred embodiment of my invention wherein the pump is employed with an internal-combustion engine 10 as a fuel pump for pumping a fuel to an engine, which in the present embodiment pumps the fuel to a fuel mixing device or carburetor 11. The pump as herein described is adapted to be preferably operated at a faster rate of speed than the engine crankshaft and preferably my pump is 45 operated by the generator driving mechanism which is usually operated at 1½ times engine crankshaft speed. Obviously, other means may be employed for driving the pump A as long as such means provide for the speed found to be 50 desirable in devices of this character.

My novel pump A comprises in general a rotor and a stator, the rotor comprising a geometric circle cylinder 12 adapted for direct driving connection with a generator drive shaft 13 by means of spiral gears 14—15; the former being carried 60 by the shaft 13, while the latter is secured to a jack shaft 16 adapted to be coupled to a rotor shaft 17 pinned or otherwise secured as at 18 to the cylindrical rotor 12.

The pump stator comprises a casing 19 having 65 a cylindrical bore 20 in which a stator member or sleeve 21 is fitted, said sleeve preferably having a press fit with said casing and fixed therein against relative rotation, the said cylindrical rotor being rotatably supported within said 70 sleeve. The sleeve is constructed to provide a plurality of pumping units 21a, 21b and 21c, which are preferably angularly spaced about the inner circular surface of the sleeve as illustrated in Figure 2. The abutments 22 of the 75 sleeve lie intermediate the pumping units and are preferably arranged with a very small clearance with said cylindrical rotor. Each pumping unit is formed from a segmental portion of the sleeve 21 (see Figure 5) and consists of an 80 arcuate fluid chamber 9, inlet and outlet openings 27 and 28 respectively, and abutments 22 at each end of the pumping unit. The fluid chamber 9 is formed by providing a segmental 85 recess in the sleeve. The clearance between the bottom of the recess or fluid chamber 9 and said rotor and the length of said chamber is dependent on the speed of the rotor and the amount of pressure and volume of fuel to be 90 delivered, and thus this clearance provides a 95 fluid chamber through which a fluid may be propelled by its adhesive and viscous action with said rotor.

In fuel pumps for internal combustion engines, a working pressure of approximately 2 lbs. is 95 required and since the permissible working pressure for any peripheral velocity depends on the length and thickness of the film in the fluid chamber, I find that with a speed of about 1½ times crankshaft speed I am able to construct a 100 fuel pump of a practical size having the necessary output by providing a clearance of approximately .010 inch between the bottom of the recess or fluid chamber and the rotor. With 105 this speed and film thickness I find I can arrange a plurality of such pumping units around the inner circular surface of the stator member or sleeve, and as shown in the drawing, said sleeve is provided with three angularly spaced 110 pumping units.

In order to carry out the principles of my invention in a practical way the stator member or sleeve 21 is provided with a pair of axially spaced annular grooves 23 and 24, the former 5 communicating with the inlet passage 25 in the casing 19 and the latter communicating with the outlet passage 26 in the casing 19. One end of each fluid chamber 9 communicates with groove 23 by a transverse passage or hole 27 10 while the other end of each fluid chamber communicates with the groove 24 by means of a transverse passage or hole 28. Thus, each pumping unit is provided with an inlet and an outlet port, and it will be noted these pumping units are operatively connected in parallel with each other, thereby providing in effect a multiple pump.

The outlet passage 26 in the casing is connected by means of a conduit 29 to the engine carburetor 11 while the inlet passage 25 is connected by means of a conduit 30 with a source of fuel supply such as a fuel tank (not shown). Preferably the inlet and outlet passages 25 and 26 respectively communicate with the inlet and outlet passages 25' and 26' in a coupling 31 arranged intermediate the casing 19 and the conduits 29 and 30. The passages 25' and 26' communicate respectively with chambers 32 and 33 in the coupling or fixture 31, and a valve 34 closes the port 40 connecting the chambers 32 and 33, this valve being preferably yieldingly seated by means of a spring 35 and so arranged as to act as a pressure relief valve to relieve any excess pressure in the outlet passages 26 and 26'.

It will thus be noted that I have provided a very compact fuel pump for an internal-combustion engine that may be economically manufactured and assembled, the casing and the stator member being preferably formed of die-castings.

Although I have illustrated but one form of my invention and have described in detail but a single application thereof, it will be apparent to those skilled in the art to which my invention pertains that various modifications and changes 45 may be made therein without departing from the spirit of my invention or from the scope of the appended claims.

What I claim as my invention is:

1. A pump structure comprising a stator having a multiplicity of angularly spaced segmental stator elements, and a cylindrical rotor cooperatively associated with said elements and rotatably supported concentrically with respect to said stator elements and radially spaced therefrom to form a shallow annular passage about the periphery of the rotor through which a fluid may be propelled by its adhesive and viscous action with said cylindrical rotor, said stator elements provided with fluid inlet and outlet means.

2. A pump structure comprising a stator having a multiplicity of angularly spaced segmental elements, and a rotor cooperatively associated with said elements and rotatably supported concentrically within said stator elements and radially spaced therefrom to form a plurality of substantially non-communicating pumping chambers circumferentially spaced about the periphery of the rotor and through which a fluid may be propelled by its adhesive and viscous action with said rotor, each of said stator elements provided with fluid inlet and outlet means communicating with said pumping chambers.

3. A pump structure comprising a stator having a plurality of angularly spaced substantially equal length segmental stator elements, and a

cylindrical rotor cooperatively associated with said stator elements and rotatably supported concentrically therewith and radially spaced therefrom to form segmental passages circumferentially spaced about the periphery of the cylindrical rod and through each of which a fluid may be propelled by its adhesive and viscous action with said rotor, each of said segmental stator elements provided with fluid inlet and outlet means communicating with said passages.

4. A pump structure comprising a casing, a member fixed within said casing and carrying a plurality of angularly spaced segmental stator elements, and a rotor cooperatively associated with said stator elements and rotatably supported in radially spaced relation concentrically therewith to form segmental chambers circumferentially spaced about the periphery of said rotor through which a fluid may be propelled by its adhesive and viscous action with said rotor, each of said stator elements provided with fluid inlet and outlet means communicating with said chambers.

5. A pump structure comprising a casing having a cylindrical bore, a sleeve fixed within said bore and constructed to provide a plurality of angularly spaced stator elements, and a rotor rotatably supported in radially spaced relation concentrically with respect to said stator elements, said rotor and stator elements having radially spaced cooperating working faces constructed to form segmental passages about the periphery of said rotor through which a fluid may be propelled by its adhesive and viscous action with said rotor, said casing and cooperating sleeve provided with fluid inlet and outlet means communicating with said passages.

6. A pump structure comprising a casing having a cylindrical bore, a sleeve fixed within said bore and constructed to provide a plurality of angularly spaced stator elements, said casing having inlet and outlet openings, said sleeve having annular grooves respectively communicating with the inlet and outlet openings carried by said casing, said sleeve having a plurality of intake and outlet passages connecting said stator elements with said grooves, and a rotor rotatably supported within said sleeve in radially spaced relation concentrically with respect to said stator elements, said rotor and stator elements having radially spaced cooperating working faces constructed to form angularly spaced segmental arcuate pump chambers through which a fluid may be propelled by its adhesive and viscous action with said rotor, the intake and outlet passages carried by said sleeve communicating with said pump chambers.

7. A pump structure comprising a casing having a cylindrical bore, a sleeve fixed within said bore and constructed to provide a plurality of angularly spaced stator elements, said casing having inlet and outlet openings, said sleeve having annular grooves communicating with the inlet and outlet openings carried by said casing, said sleeve having a plurality of radially extending intake and outlet passages connecting said stator elements with said grooves, and a geometric circle cylindrical rotor rotatably supported within said sleeve in radially spaced relation concentrically with respect to said stator elements to form passages extending about the periphery of the rotor through which a fluid may be propelled by its adhesive and viscous action with said rotor.

8. A fuel pump for an internal-combustion engine including a crankshaft and having a shaft rotatable at a speed in excess of said crank-shaft, said pump comprising a stator having 5 fluid inlet and outlet ports, a rotor rotatably supported in radially spaced relation concentrically within said stator, said stator and rotor having radially spaced cooperating working surfaces constructed to form a plurality of angularly 10 spaced segmental passages about the periphery of said rotor through which a fluid may be propelled by its adhesive and viscous action with said rotor, and driving means for operatively connecting said rotor with said shaft.
- 15 9. A fuel pump for an internal-combustion engine having a generator and generator driving mechanism including a shaft, said pump comprising a stator having fluid inlet and outlet ports, a rotor rotatably supported within said 20 stator in spaced relation therewith, said stator and rotor having radially spaced cooperating working surfaces constructed to form an arcuate segmental passage about the periphery of the rotor through which a fluid may be propelled by 25 its adhesive and viscous action with said rotor, and driving means for operatively connecting said rotor with said generator driving shaft and thereby driven at a speed in excess of said crankshaft.
- 30 10. A pump structure comprising a stator having a multiplicity of angularly spaced segmental stator elements, and a rotor cooperatively associated with said elements and rotatably supported concentrically with respect to said stator 35 elements and radially inwardly spaced therefrom to form a passage through which a fluid may be propelled by its adhesive and viscous action with said rotor, said stator elements provided with fluid inlet and outlet means, and 40 pressure relief valve means intermediate said fluid inlet and outlet means actuated in response to pressure of the fluid in said outlet means.
11. A pump structure comprising a stator having a multiplicity of angularly spaced segmental stator elements, and a rotor cooperatively associated with said elements and rotatably supported in radially spaced relation concentrically within said stator elements to form 45 passages through each of which a fluid may be propelled by its adhesive and viscous action with said rotor, said stator elements each provided with fluid inlet and outlet means, said pump structure having a by-pass connecting said fluid inlet and outlet means, and a yieldingly 50 supported pressure relief valve means responsive to the fluid pressure in said outlet means for controlling the fluid flow through said by-pass.
- 55 12. A fuel pump structure for an internal- 60
- combustion engine comprising a casing having a cylindrical bore, a cylindrical stator member fixed within said bore and provided with a plurality of angularly spaced arcuate stator elements, and a cylindrical rotor rotatably supported and spaced radially inwardly with respect to said arcuate stator elements to form 80 passages through each of which a fluid may be propelled by its adhesive and viscous action with said rotor, said casing and stator member constructed of die castings. 85
13. A fuel pump structure for an internal-combustion engine comprising a casing having fluid inlet and outlet means, a cylindrical stator member fixed within said casing and having a pair of axially spaced annular grooves in the outer cylindrical face thereof, one of said grooves communicating with the inlet means and the other of said grooves communicating with the outlet means of said casing, said stator member provided with a plurality of angularly spaced arcuate stator elements adjacent the inner circular surface of the stator member and each provided with an inlet passage communicating with the groove connected with said inlet 90 means of said casing and with an outlet passage communicating with said other groove connected with said outlet means of said casing, and a rotor rotatably supported concentrically with respect to said arcuate stator elements to 95 form arcuate pump chambers about the periphery of said rotor through each of which a fluid may be propelled by its adhesive and viscous action with said rotor. 100
14. A fuel pump for an internal combustion engine and including a casing having a stator member provided with a plurality of angularly spaced arcuate stator elements and fluid abutments intermediate said stator elements and a rotor supported for rotation concentrically within said stator member, said rotor and associated stator member constructed and cooperating to provide a plurality of angularly spaced segmental pump chambers about the 110 periphery of said rotor, said rotor having minimum clearance with respect to said abutments to permit relative rotation of said rotor with respect to the stator element but acting to dam the flow of fluid induced by the adhesive and 115 viscous action of the fluid with said rotor, said stator member having passages forming fluid inlet and outlet means for each of said pump chambers, said casing having fluid inlet and outlet means respectively associated with said 120 inlet and outlet means carried by said stator member. 125
